BATTERY TERMINAL POST CLEANING DEVICE

John J. Williams, Bridgeport, Conn.

Application April 18, 1944, Serial No. 531,675

15 Claims. (Cl. 51—186)

1

This invention relates to tools for use with storage batteries and the like, and more particularly to a cleaning tool for removing dirt, corrosion, acid deposits, etc., from the terminal posts of a battery.

An object of the present invention is to provide an improved cleaning tool for battery terminal posts which will operate to efficiently remove dirt and crusted deposits without removing any substantial amount of metal of the post which would cause undesirable reduction in the post diameter. The invention also aims to provide a cleaning tool of such construction that acid conditions under which the tool is used will not necessitate frequent replacement of the tool.

These objects are accomplished by the provision, in a plier-like battery tool of a pair of jaws having concave surfaces carrying abrasive particles or grits such as medium fine emery cloth and preferably so arranged that when the tool is rotated about its axis, the surface of the battery post which the jaws embrace will be cleaned and polished. Preferably, the novel structure is such as to permit quick and convenient removal and replacement of the cleaning jaws.

The nature of storage batteries, with their acid electrolyte, is such that heavy corrosion generally occurs at the terminals due to the action of the acid on the same. Cleaning implements heretofore used for removing the dirt and corrosive deposits on the terminal posts employed a scraping and trimming action which resulted in removal of a considerable amount of metal from the post. This undesirably reduced the post diameter so that the terminal clamps would no longer clamp same tightly without shims. This, together with the inconvenience accompanying the use of these prior cleaning tools, caused them to be often left on the bench and not used, so that the battery remained in an unclean state. By the provision of quickly removable and replaceable jaws in a cleaning tool, the present invention makes it possible to conveniently clean battery terminal posts, and to employ a mild, fine abrasive type of cleaning action. This latter was previously not practicable because when in use the jaws would become clogged if substantial amounts of dirt and deposits were encountered on the posts, and time would then be required to clean the jaws before the operation could be completed. However, with the device of the present invention, when the cleaning jaws have become clogged with dirt or worn out, it is a simple matter to quickly remove and re-

2

place these jaws with a new clean set, and proceed with the cleaning operation. The jaws which are removed may be conveniently cleaned and if necessary provided with new abrasive at a later time, so that they are again ready for use.

As a result of these advantages, an incentive is provided for cleaning the terminal posts of a battery, and this operation may be quickly and conveniently accomplished, without detriment to the posts. Moreover, whatever corrosion of the cleaning jaws of the tool might occur due to the acidity of the deposits removed from the battery posts, it will not affect the main part of the tool, so that the latter has an extended period of usefulness. The demountable jaws of the tool may be removed after a number of cleaning operations and washed with soap or other solution or cleaned with a brush, and the jaw-supporting parts of the tool readily wiped clean because of their simple shape.

According to this invention, the demountable jaws are made so as to be of low cost, being formed of sheet metal with an abrasive means attached thereto. In one form of the invention this abrasive means comprises a strip of emery cloth or the like held on the jaw and in another form the abrasive means comprises emery particles or grits attached to the jaw surface with suitable adhesive.

Other features and advantages will hereinafter appear.

In the accompanying drawing—

Figure 1 is a front elevation of a cleaning tool made according to one form of the invention, placed on a battery post for cleaning same.

Fig. 2 is a side elevation of the tool of Fig. 1.

Fig. 3 is a vertical section taken on the line 3 of Fig. 2.

Fig. 4 is a horizontal section taken on the line 4—4 of Fig. 1.

Fig. 5 is a horizontal sectional view similar to that of Fig. 4, but showing a modified form of the invention.

Fig. 6 is a perspective view of one of the cleaning jaws of the tool illustrated in Fig. 5, and

Fig. 7 is a perspective view of a modification of the cleaning jaw illustrated in Fig. 6.

Referring to Figs. 1 through 4, the improved cleaning tool of this invention comprises a pair of levers 10 and 11 pivotally connected together intermediate their ends by a pin 12. The levers have handle portions 10a and 11a respectively, and on the opposite side of the pin 12, shorter jaw-supporting portions 10b and 11b respectively,

According to the present invention in the form illustrated in Figs. 1, 2 and 3, the supporting portions 10b and 11b of the tool are provided with demountable cleaning jaws so that the latter may be quickly and conveniently removed when clogged with dirt, and may be cleaned and replaced, or else immediately replaced by another clean set of jaws.

For this purpose the ends 13 and 14 of the supporting arms 10b and 11b respectively may be provided with apertures 15 and 16 extending substantially parallel to the axis of the pin 12. Carried on the ends 13 and 14 are resilient mounting clips 17 and 18 respectively which are fastened to cleaning jaws 19 and 20 in some suitable manner, as by welding, each clip having a U-shape, and the yoke of the clip being attached to the associated jaw. The ears of the clips 17 and 18 are provided with extruded inwardly extending projections 21 and 22 respectively which enter and engage the walls of the apertures 15 and 16 respectively, and bottom tabs 23 and 24 are provided, bent to form closures for the bottom sides of the clips.

The cleaning jaws 19 and 20 are shaped to substantially encompass and engage a battery terminal post 25, and this shape may be such that, when spaced slightly apart as shown in Figs. 1 and 3, the jaws constitute substantially a frusto-conical two-piece shell, each jaw comprising slightly less than one-half of the frustum of a cone. The base or bottom edges of the jaws preferably are flared outwardly, as shown at 19b and 20b, to prevent them from cutting into the material of the base 25a of the post 25.

For the purpose of cleaning the surface of the post 25 without removing an excessive amount of metal therefrom, the jaws 19 and 20 are provided on their inner surfaces with abrasive material. This may be in the form of emery cloth or other suitable sheet abrasive material, the edges of the cloth being held by folding over inwardly the vertical edges 26 and 27 of the jaws respectively to clamp said edges.

When using a cleaning tool constructed according to the invention, as described above, the terminal posts of a battery may be quickly and conveniently cleaned. This is done by grasping the handle portions 10a and 11a of the tool, placing the jaws 19 and 20 about the post to encircle the same, and then rotating the tool about the axis of the post preferably by a to and fro oscillating movement. This will result in the grits of the abrasive removing any corrosion or oxidation or foreign matter on or embedded in the relatively soft metal post, yet the amount of metal removed therefrom during this operation will be substantially nil so that the diameter of the post is not reduced undesirably.

Should the corrosion and dirt on the battery posts be considerable enough to clog the pores of the abrasive medium carried by the jaws 19 and 20 so that this medium is no longer effective, the jaws may be cleaned, or may be quickly removed and replaced by a new set, and the cleaning process continued.

It will be noted that the tabs 23 and 24 of the spring clips protect the ends 13 and 14 of the supporting arms from contact with corrosive deposits removed from the battery posts during the cleaning thereof. It is therefore unlikely that these ends would become corroded during normal use of the tool, and those parts of the tool, namely the jaws 19 and 20 which are subjected to the action of the corrosive deposits, being

readily removable, may be conveniently cleaned as by washing with a soap solution. Preferably these jaws are made of a corrosion-resistant sheet material such as stainless steel. Thus the useful life of the tool of this invention will be comparatively long.

After continued use of the tool, should the abrasive medium on the jaws 19 and 20 become worn away, the jaws may be discarded and new jaws used instead.

A modification of the invention is shown in Figs. 5 and 6. In this modification, the ends 13a and 14a of the supporting arms of the tool may be forked or bifurcated to receive deep longitudinal crimps 28 and 29 respectively which are formed in the central portions of the cleaning jaws 19a and 20a. As shown in Fig. 6, an abrasive cloth 30 along its central portion extends into the crimp 28 of the jaw 19a and is securely held in place thereby.

For the purpose of fastening the jaws 19a and 20a to the ends 13a and 14a respectively of the supporting arms, the latter are apertured, and the crimps 28 and 29 correspondingly apertured to receive pins 31 and 32 respectively.

The functioning of this form of the invention is similar to that shown in Figs. 1 through 4, the pins 31 and 32 being frictionally held in place so that they may be quickly removed for detaching the jaws when desired.

Fig. 7 illustrates a modified form of cleaning jaw 33 which is interchangeable with the jaws 19a and 20a. This modified jaw has a sheet metal body portion 34 which is backed by folds 35 and 36 in the metal, the end portions 37 and 38 of the folds being bent to extend radially from the body 34 to form an ear 39. This ear has an aperture 40 and functions to support the jaw in the same manner as the crimps in the jaws 19a and 20a.

According to this invention, an abrasive medium need not be in the form of a sheet, but may be provided on the inner surface of the jaw in the form of a coating 41 of emery or other grits which may be applied with a suitable adhesive as shown in Fig. 7. This coating may be cleaned with a brush and soap solution when it becomes clogged, and may be readily renewed from time to time so that the jaws need not be discarded after a certain period of use.

Variations and modifications may be made within the scope of the invention and portions of the improvements used without others.

I claim:

1. A battery terminal post cleaning tool comprising a pair of hand levers pivotally connected together intermediate their ends, each of one pair of adjacent ends being bifurcated; a pair of sheet metal jaws, one for mounting on each of said bifurcated ends, each of said jaws having substantially a semi-cylindrical shape and a longitudinally-extending tab along its central portion, interposed between the forks of its supporting lever end, the longitudinal edges of each jaw being folded, an abrasive lining for each jaw, having portions interposed in the folds of the jaw edges for holding the lining against incidental removal; and pin means extending through the tabs of the jaws and the associated lever end for fastening same together.

2. A battery terminal post cleaning tool comprising a pair of hand levers pivotally connected together intermediate their ends, each of one pair of adjacent ends being bifurcated; a pair of sheet metal jaws, one for mounting on each of said

bifurcated ends, each of said jaws having substantially a semi-cylindrical shape and a longitudinally-extending crimp along its central portion, the crimp being interposed between the forks of its supporting lever end and the longitudinal edges of each jaw being folded; an abrasive lining for each jaw, having portions interposed in the folds of the jaw edges and in the crimp of the jaw for holding the lining against incidental removal; and pin means extending through the crimps of the jaws and the associated lever end for fastening same together.

3. A battery terminal post cleaning tool comprising a pair of hand levers pivotally connected together intermediate their ends, each of one pair of adjacent ends being bifurcated; a pair of sheet metal jaws, one for mounting on each of said bifurcated ends, each of said jaws having substantially a semi-cylindrical body portion and folds backing said body portion, the end portions of said folds being bent on adjacent longitudinal lines extending along the central part of the body portion so that said end portions extend radially outward to form an ear of double thickness between the forks of the associated lever end; abrasive means on the body portion of each jaw; and pin means extending through the ears of the jaws and the associated lever ends for fastening same together.

4. A battery terminal post cleaning tool comprising a pair of hand levers pivotally connected together intermediate their ends, each of one pair of adjacent ends being bifurcated; a pair of sheet metal jaws, one for mounting on each of said bifurcated ends, each of said jaws having substantially a semicylindrical body portion and folds backing said body portion, the end portions of said folds being bent on adjacent longitudinal lines extending along the central part of the body portion so that said end portions extend radially outward to form an ear of double thickness between the forks of the associated lever end; an abrasive coating on the body portion of each jaw; and pin means extending through the ears of the jaws and the associated lever ends for fastening same together.

5. A battery terminal post cleaning tool comprising a pair of hand levers pivotally connected together intermediate their ends, each of one pair of adjacent ends being bifurcated; a pair of sheet metal jaws, one for mounting on each of said bifurcated ends, each of said jaws having substantially a semi-cylindrical shape and a longitudinally-extending crimp along its central portion, the crimp being interposed between the forks of its supporting lever end; and abrasive lining for each jaw, having central portions interposed in the crimp of the jaw for holding said portions in place; means extending along the longitudinal edges of each jaw for holding the edge portions of the abrasive lining in place; and pin means extending through the crimps of the jaws and the associated lever end for fastening same together.

6. A battery terminal post cleaning tool comprising a pair of hand levers pivotally connected together; a pair of jaws adapted to engage the convex surface of a battery terminal post, having abrasive grits on the post-engaging surfaces thereof; and means for pivotally mounting the jaws on the adjacent ends of the levers respectively for movement about axes parallel to the axis of the pivotal axis of the hand levers so that they may be made to embrace and rotate about the terminal post for cleaning same.

7. A jaw for a terminal post cleaning tool

comprising a body and means for mounting same on a holder, said body being adapted to engage the convex surface of a terminal post; an abrasive lining for the body; and means including means for frictionally securing the lining to opposite edges and separate means to engage and hold the center portion of the body to prevent its incidental removal.

8. A jaw for a terminal post cleaning tool comprising a substantially semi-cylindrical sheet metal body and folds backing said body, the end portions of the folds being bent on adjacent longitudinal lines extending along the central part of the body so that said portions extend radially outward to form a mounting tab of double thickness; and abrasive means on the body for cleaning the terminal post when the latter is engaged and rubbed by said body.

9. A jaw for a terminal post cleaning tool, comprising a body having a substantially semi-cylindrical shape and a longitudinally-extending crimp along its central portion, the longitudinal edges of the body being folded; and an abrasive lining for the body, having portions interposed in the folds of the body edges and in the crimp thereof to hold the lining against incidental removal.

10. A battery terminal post cleaning tool comprising a pair of hand levers pivotally connected together intermediate their ends, each of one pair of adjacent ends being bifurcated; a pair of sheet metal jaws, one for mounting on each of said bifurcated ends, each of said jaws having substantially a semi-cylindrical shape and a longitudinally-extending tab along the back central portion, interposed between the forks of its supporting lever end, the front portion of each jaw being covered with an abrasive material; and pin means extending through the tabs of the jaws and the associated lever end for fastening same together.

11. A battery terminal post cleaning tool comprising a pair of hand lever members pivotally connected together intermediate their ends; a pair of sheet metal jaw members; means for mounting the jaw members on lever members including a longitudinal rib-like portion on one member and a pair of longitudinally disposed elements on the other member spaced to receive the rib-like portion therebetween and means detachably connecting the assembled longitudinal rib-like portion and longitudinally disposed spaced elements together to secure the jaw members to the lever members, each of said jaws having substantially a semi-cylindrical shape, the longitudinal edges of each jaw being folded; and an abrasive lining for each jaw, having portions interposed in the folds of the jaw edges for holding the lining against incidental removal.

12. A battery terminal post cleaning tool comprising a pair of hand lever members pivotally connected together intermediate their ends; a pair of sheet metal jaw members; and means for mounting the jaw members on lever members including a longitudinal rib-like portion on one member and a pair of longitudinally disposed elements on the other member spaced to receive the rib-like portion therebetween and means detachably connecting the assembled longitudinal rib-like portion and longitudinally disposed spaced elements together to secure the jaw members to the lever members, each of said jaws having substantially a semi-cylindrical shape, the longitudinal edges of each jaw being

folded and the terminal post engaging face there-between being covered with an abrasive material.

13. A battery terminal post cleaning tool comprising a pair of hand levers pivotally connected together; a pair of jaws shaped to engage the convex surface of a battery terminal post and having means for cleaning said surface; and means for mounting the jaws on the adjacent ends of the levers respectively to position them for gripping and cleaning the terminal post, said mounting means comprising spring arms and interlocking cooperating portions carried by the jaws and levers to form readily releasable snap-connectors whereby the jaws may be quickly attached or removed without the use of tools.

14. A battery terminal post cleaning tool comprising a pair of hand levers pivotally connected together and having recesses formed in opposite surfaces of the jaw-supporting ends thereof; a pair of jaws shaped to engage the convex surface of a battery terminal post and having means for cleaning said surface; and means for mounting the jaws on the adjacent ends of the levers

respectively to position them for gripping and cleaning the terminal post, said mounting means comprising resilient clips attached to each jaw to embrace the associated lever end and having projections engaging the walls of the recesses to yieldably hold the jaws on the levers.

15. A battery terminal post cleaning tool comprising a pair of hand levers pivotally connected together and having apertures in the jaw-supporting ends thereof; a pair of jaws shaped to engage the convex surface of a battery terminal post and having means for cleaning said surface; and means for mounting the jaws on the adjacent ends of the levers respectively to position them for gripping and cleaning the terminal post, said mounting means comprising resilient clips attached to each jaw to embrace the associated end lever and having integral projecting bosses engaging the walls of the recesses to yieldably hold the jaws on the levers.

JOHN J. WILLIAMS.
